Primary Examiner — Susan Moon Lee

CLAIM

The ornamental design for a beverage container with bowl, as shown and described.

DESCRIPTION

FIG. 1 is a front view of a beverage container with bowl showing my new design;

FIG. 2 is a side view thereof;

FIG. 3 is a top perspective view thereof;

FIG. 4 is a bottom perspective view thereof;

FIG. 5 is an exploded top perspective view thereof;

FIG. 6 is a top view thereof; and,

FIG. 7 is a bottom view thereof.

All broken lines in the drawings are for illustrative purposes only and form no part of the claimed design.

1 Claim, 6 Drawing Sheets
